COMBINED ASH RECEPTACLE AND DRAFT CONTROLLING DOOR FOR DOMESTIC WATER HEATERS, STOVES, AND THE LIKE

Daniel G. Burkert, Boyertown, Pa.

Application June 14, 1945, Serial No. 599,409

2 Claims. (Cl. 126—243)

1

My invention relates to combined ash receptacles and draft controlling doors for domestic water heaters, stoves, and the like.

My invention contemplates the provision of an ash pan adapted to receive ashes from the fire chamber of a domestic stove, particularly of the type which are used for heating water and commonly known as tank heaters. The invention further contemplates the provision of an ash pan which is so constructed and arranged as to receive the ashes as the same fall through the grate, and also serve to scoop up any ashes which may fall while the ash pan is removed from its normal position beneath the grate.

One of the principal objections to tank heaters, as the same are now made, is the limited capacity of the ash pit, and it frequently occurs that the ash pit becomes filled and clogged because means for removing the ashes are not always readily available.

The principal object of the present invention is to provide an ash pan which is adapted to receive the ashes from the grate of the stove or furnace as the same fall through the grate, whereby the ashes may be readily and conveniently removed without requiring the use of a special shovel for such purpose.

A further object of the invention is to provide an ash pan, of the character aforesaid, which is so constructed and arranged as to form a scoop which may be used to gather up any ashes which may fall on the floor of the ash pit while the ash pan is removed, thus eliminating the necessity for a special shovel for such purpose.

A further object of the invention is to provide an ash pan, of the character aforesaid, which is so constructed and arranged that the draft may be easily regulated, and which will eliminate the possibility of shutting off the draft through stoppage by the ashes accumulating within the ash pan.

A further object of the invention is to provide an ash pan, of the character aforesaid, which may be inexpensively constructed, and which will be adaptable for use in connection with the domestic water heaters at present in common use.

The nature and characteristic features of the invention will be more readily understood from the following description, taken in connection with the accompanying drawings forming part hereof, in which:

Figure 1 is a vertical central section of the base portion of a water heater of a well known type, with an ash pan embodying the main features

of the present invention shown in connection therewith;

Fig. 2 is a perspective view of the ash pan of the present invention removed from the heater;

Fig. 3 is a front elevation of a portion of the structure shown in Fig. 1;

Fig. 4 is an enlarged sectional detail view of the front end portion of the ash pan detached; and

Fig. 5 is a sectional view taken approximately on the line 5—5 of Fig. 4, but with a portion of an internal partition partially broken away.

It should, of course, be understood that the description and drawings herein are illustrative merely, and that various modifications and changes may be made in the structure disclosed without departing from the spirit of the invention.

Referring to the drawings, the device of the invention is therein shown in connection with a base portion 10 of a water heater, of the type commonly known as a "tank heater," ordinarily used for maintaining a domestic supply of hot water, and for auxiliary heating plants of small radiator capacity. In such tank heaters the water section 11 rests upon the base 10 and encloses the fire chamber 12 below which the grate 13 is mounted. The grate 13 may be any of the types commonly used in connection with stoves or with water heaters of the type above mentioned.

The usual front or door frame casting of the heater base 10 is omitted and in lieu thereof there is provided a casting 10^a which serves as a support for the front ends of the shafts 14 of the grate members 13, when a rocking grate, or a grate of the rotating section type is employed.

The ash pan, comprising the principal novel portion of the present invention, is shown in detached perspective in Fig. 2 of the drawings, and the front plate 15 thereof normally forms a closure for the opening in the front of the ash pit which in the water heaters as heretofore made are closed by the door frame casting and the door carried thereby.

Secured to the front plate 15 of the ash pan is a scoop like structure, comprising side plate 16, and a bottom plate 17 which normally rests on the floor of the ash pit. The forward end of the scoop like structure thus provided is left open but the bottom plate 17 preferably extends beyond the ends of the side walls 16 to provide a lip 18 extending forwardly. If desired a brace 19 may extend across connecting the side walls 16 at their forward ends.

The front plate 15 of the ash pan is also provided with a handle 20, preferably extending vertically and located centrally between the ends of said plate.

The front plate 15 of the ash pan is also provided with a plurality of vertically extending slots 21, and a plate 22, similarly slotted as at 23, is slidably mounted on the inner face of said plate member 15 preferably by means of rail members 24. The slideable plate member 22 has a knob 25 secured thereto, the shank 26 of which extends through a horizontal slot 27 in the front plate 15 thereby to permit the manual actuation of the slideable plate 22 for the purpose of closing or opening the slots provided in the front plate of the ash pan to regulate the amount of air supplied below the grate.

To the rear of the front plate 15 there is provided an inclined partition 28 which is secured at its sides to the side walls 16 of the ash pan, which partition 28 will effectively serve to prevent the ashes which accumulate in the ash pan from closing the openings through which the air is supplied to the space below the grate.

It will be seen that by the foregoing arrangement there is provided a simple, efficient, and relatively inexpensive device by means of which the ashes which fall through the grate may be readily and expeditiously removed from time to time, and that the same is so constructed and arranged that there will be no possibility of the draft being stopped, or even modified, by the ashes which accumulate in the ash pan between the times of the removal of the same, and an unobstructed conduit for the air which passes through the apertures in the front plate will be maintained at all times.

I claim:

1. An ash pan for use in connection with water heaters, stoves, and the like having an ash pit provided with a front opening, comprising a device having a front plate 15, a handle 20, a plurality of vertically extending slots 21, a slideable plate member 22, a knob 25, a shank 26, a horizontal slot 27, and an inclined partition 28.

vice having a vertically disposed front plate which normally constitutes a closure for the front opening of the ash pit, a bottom plate and side walls extending from said front plate to form a scoop-like structure open at its inner end, the front plate being provided with apertures, means adapted to open and close said apertures, and a partition in the device adjacent the front plate to provide an unobstructed conduit for air passing through the apertures in the front plate.

5 2. An ash pan for use in connection with water heaters, stoves, and the like having an ash pit provided with a front opening, comprising a device having a vertically disposed front plate which 15 normally constitutes a closure for the front opening of the ash pit, a bottom plate and side walls extending from said front plate to form a scoop-like structure open at its inner end, the front plate being provided with apertures, a complementally 20 apertured plate slidably mounted on said front plate and adapted to open and close said apertures, and a rearwardly inclined partition in the 25 device adjacent the front plate forming in conjunction therewith an unobstructed conduit for air passing through the apertures in the front plate.

DANIEL G. BURKERT.
